COMBINED BUSINESS REPLY POST CARD
AND ENVELOPE

Emanuel Feder, Newark, N. J.

Application August 30, 1941, Serial No. 409,007

1 Claim. (Cl. 229—73)

My invention relates to a one-piece business reply post card and business reply envelope of the type in which postage is guaranteed by the addressee under the postal laws and regulations.

Normally, such business reply cards and envelopes are separately distributed depending on the purpose for which the cards or envelopes were sent. In many instances envelopes are distributed when post cards would be satisfactory. Since the postal charge on a business reply postal card is generally one-half of the cost of a business reply envelope, a considerable saving can result if the proper type mailing piece is returned to the addressee.

Accordingly, it is the primary object of my invention to combine a business reply card and a business reply envelope into a one-piece unit, which will permit the addresser to select either the card or the envelope, or to use the unit.

The postal laws and regulations (section 508), require that post cards manufactured by private parties may not depart from fixed prescribed dimensions, and that the weight of the stock used be substantially that of the type used in Government post cards.

A further object of my invention, therefore, is to provide my one-piece business reply post card and business reply envelope with dimensions and weight of stock complying with the foregoing postal requirements.

I have further found my one-piece business reply card and envelope to be desirable for insertion into magazines, for various purposes such as renewals, new subscriptions, gift subscriptions, etc., by use of the business reply card when such subscription is charged, or if payment is made, it may be enclosed in the reply envelope.

Hitherto, a business reply envelope, when used as a magazine bind, was provided with lateral flaps extending for a height equal to the height of the closing flap and envelope body. Thus, a further objects consists in providing means whereby my one-piece business reply card and envelope may be inserted into the binding of a magazine where either the card or envelope or both, may be withdrawn.

I accomplish these and other objects and obtain new results as will be apparent from the device described in the following description, particularly pointed out in the attached claim, and illustrated in the accompanying drawing, in which:

Fig. 1 is a plan view of my one-piece business reply card and envelope, in the open position.

Fig. 2 is the reverse view of the same.

Fig. 3 is a partially sectioned view showing the envelope closed.

Fig. 4 is a view showing my combined post card and envelope used as a bind in a magazine.

Referring more in detail to the drawing and more particularly to Fig. 1, reference numeral 11 designates the front panel of my one-piece return post card and envelope 10. Integrally attached thereto are, upper flap 12, lower flap 13, right marginal flap 14, and extending post card 15.

In order to form and seal the envelope, I preferably gum the upper border 16 of the upper flap 12, and the two side borders 17 and 18 of the lower flap 13.

The stock of my combined business reply post card and envelope is preferably made of 100 pound paper stock or any weight satisfactory for use as a Government post card, as indicated in section 508, subsection b, of the postal laws and regulations, and is provided with fold lines 20, 21, and 22 separating the top flap 12, side margin flap 14, and lower flap 13, respectively, from the front panel 11 so that the respective elements may be folded into position and glued to form an envelope.

The post card 15 may be detached from the envelope panel 11 at the line of perforations 19 positioned at the junction of the post card 15 and the panel 11.

The device 10 is provided to the user preferably in the form of an envelope and card. Thus, right marginal flap 14, is folded up along fold line 21 and lower flap 13, is similarly folded up along fold line 22, with the gummed portion 18, engaging the flap 14, and gummed portion 17, engaging the panel 11.

In this position the post card 15 may be folded up on perforations 19 by the addresser, and the upper flap 12 folded up on fold line 20 with the gummed portion 16 engaging the back of lower flap 13. This may be accomplished by making the height of post card 15 less than the height of panel 11, by a distance A, sufficient to allow the gummed portion 16 on upper flap 12 to engage the lower flap 13. The length of the card 15 should be less than the length of the panel 11, as shown in Fig. 3. Furthermore, it is possible to omit marginal flap 14, and attach lower flap 13, directly to panel 11 by gummed portions 17 and 18.

Thus, it is possible to return the post card with the envelope without additional charge for the card.

55 In practice the front portion of the post card

15 may have imprinted thereon the facing required for mailing under the postal laws and regulations. This also applies to the front panel 11, as shown in Fig. 2.

The remaining sides of the card and envelope shown in Fig. 1 may have advertising printed thereon and/or requests for further information for a sample, for various advertisements, for a salesman, for a subscription, etc., all of which may be checked off by the addresser. In addition, the name and address of the user may be imprinted on these faces of the card and envelope by the same machine that addresses the magazine or original mailing piece. This enables the addresser to merely check the card or envelope without loss of identity. The card alone may be used. In the event the addresser wishes to include a payment, he may enclose it directly in the envelope. If he wishes to make some request printed on the card, as well, he may do so and fold the card and enclose the money within the envelope.

Thus, one postal charge only will be made regardless of whether card and/or envelope are used, and the choice is possible which involves the minimum postal charge.

My one-piece card and envelope may be inserted as a bind in a magazine, as shown in Fig. 4, wherein the magazine 30 is indicated with my device inserted between the staples 31, which permits the free withdrawal of the entire device from the magazine on the envelope side. In this view the post card 15 is shown in dotted line behind the magazine leaves 32.

Where it is necessary to permanently bind the device 10 to a magazine or book, the marginal flap 14 may be left extending from panel 11, with lower flap 13, gummed directly to front panel 11, and flap 14 utilized as the portion that is permanently bound into the magazine or book. In this instance the fold line 21 may be perforated.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claim, and by means of which objects of my invention are attained and new results accomplished, as it is obvious that the particular embodiments herein shown and described are only some of the many that may be employed to attain these objects and accomplish these results.

I claim:

A device for mailing comprising an elongated rectangular front panel, a top flap, and a lower flap integrally connected by fold lines along the longitudinal edges of the front panel substantially throughout the length thereof; said top flap having its upper border provided with an adhesive or gummed substance; means for sealing said panel and upper and lower flap to form an envelope body closed on all four sides of the front panel; card means integrally connected along a transverse edge of said envelope body and in spaced relation to the fold line of the lower flap, and provided with means to facilitate detachment from the envelope body, said integral card means being spaced from said lower fold line sufficiently to enable it to be folded along the attached transverse edge and allow the upper flap to be sealed to the lower flap, without the adhesive or gummed substance engaging the integral means; said integral means having a size and weight of material required for use as a postal card.

EMANUEL FEDER.
